UNITED STATES PATENT OFFICE

144,688

DESIGN FOR A BASE FOR A FILM SPLICER

Jack Briskin, Chicago, Ill., assignor to Revere Camera Company, Chicago, Ill., a corporation of Delaware

Application December 7, 1945, Serial No. 124,464

Term of patent 14 years

(Cl. D61—1)

To all whom it may concern:

Be it known, that I, Jack Briskin, a citizen of the United States and a resident of Chicago, in the county of Cook and State of Illinois, have invented a certain new, original, and ornamental Design for a Base for a Film Splicer, of which the following is a specification, reference being had to the accompanying drawing, forming part thereof, in which,

Fig. 1 is a plan view of a base for a film splicer embodying my new design, the broken lines indicating the outline of the film splicer which is adapted to be mounted on said base, but said broken lines being omitted from Figs. 2 and 3 for convenience of illustration;

Fig. 2 is a front elevation of the base shown in Fig. 1; and

Fig. 3 is a right hand end view thereof.

I claim:

The ornamental design for a base for a film splicer, substantially as shown and described.

JACK BRISKIN.
